BUILDING UNIT AND METHOD OF
MANUFACTURE THEREOFLester Kirschbraun, New York, N. Y., assignor to
The Patent and Licensing Corporation, New
York, N. Y., a corporation of Massachusetts

Application April 16, 1935, Serial No. 16,557

3 Claims. (Cl. 20—5)

This invention relates to a form of building unit and is more particularly concerned with the production of a unit adapted to serve as a covering for the vertical side walls of buildings.

5 One of the objects of the invention is to provide a building unit which can readily be made by preforming the main body portion of the unit from a plastic composition of water-resistant character.

10 Another object of the invention is to provide a unit of this type in which the body portion of plastic composition is reinforced on the lower face thereof with a thin sheet of flexible felted material, and on the opposite face thereof, which is to be exposed to the weather, with a sheet of flexible material carrying a surfacing layer of mineral grit such as that commonly employed in making roofing, for the purpose of imparting to the finished unit desired ornamental effects.

20 In its preferred form, the unit of my invention is designed to simulate the appearance of brick or other masonry construction when a plurality of the units are laid in proper relation on a vertical side wall; and to this end, the preferred 10 form of the unit is formed along its upper and lower longitudinal margins with flanges so arranged and dimensioned that when properly assembled, the flange on the lower longitudinal boundary of one unit will cooperate with the 15 flange on the upper longitudinal boundary of the subjacent unit to provide an efficient lap between the adjacent units and at the same time leave a longitudinally extending depression between certain portions of the adjacent units to simulate 20 horizontal mortar lines of brick or other masonry construction.

25 With the foregoing and other objects in view, I have designed the unit, and a method for making the same, to be more fully hereinafter described, depicting the same, as well as can be, in the accompanying drawings, in which:—

30 Figure 1 shows, in perspective, a unit constructed in accordance with the invention;

Fig. 2 is a transverse cross-section through the 35 unit along line 2—2 of Fig. 1;

Fig. 3 is a plan view of an assembly of such units as they would appear when laid;

Fig. 4 is a vertical section taken along the line 40 4—4 of Fig. 3;

Fig. 5 is a view, partly in perspective and partly in cross section, showing one method by which the units of my invention may be produced; and

Fig. 6 is an elevational view of the forming rolls shown in Fig. 5 for use in carrying out the method 45 of producing the units.

Referring first to Figs. 1, 2 and 4, the unit as therein shown comprises essentially a main core or body portion 10, elongated in its longitudinal dimension, a reinforcing sheet 11 on the lower face thereof, and a reinforcing sheet 12 on the upper face thereof.

The core 10 is constituted of a hardened plastic mixture consisting essentially of asphalt, fiber and mineral or other hardening fillers such as ground slate, talc, mica or the like, or combinations thereof. The proportions of the several ingredients constituting the core may vary within considerable limits so long as the composition has the character of being plastic at elevated temperatures but substantially rigid at normal atmospheric temperatures. From the standpoint of convenience and economy, this core may consist of disintegrated and homogenized scrap or waste asphalt roofing, substantial quantities of which are ordinarily accumulated in the manufacture of asphalt prepared roofing. This scrap of waste material is generally composed of about 50 to 60% asphalt, 15 to 20 fiber and 25 to 35% mineral matter. If necessary or desirable, the scrap may be compounded with further quantities of asphalt, fiber and mineral or organic filler sufficient to impart the desired rigidity and strength. Within the limits above stated, the composition of the core may readily be made such that at temperatures of from 200 to 300° F., 30 it can be extruded or otherwise formed under pressure to desired shape. In order still further to indicate the character of the core composition, it may be stated that, as distinguished from ordinary asphalt or mineral filled asphalt compositions such as are normally employed for coating prepared roofing, the core composition to be employed in accordance with my invention, while deformable under pressure and at elevated temperatures, is not liquefiable by heat as are 35 the ordinary asphalt or mineral filled asphalt coatings. In fact, the mastic asphalt composition here contemplated and containing fiber and mineral filler admixed in the proportions above indicated with the asphalt, are practically infusible at elevated temperatures; and as already stated, it assumes a substantially rigid condition at normal atmospheric temperatures, whereas ordinary asphaltic coatings even when containing substantial amounts of mineral filler are 40 in no sense self-sustaining.

The core 10 of the unit is formed along the upper longitudinal boundary thereof with a flange 15 by depressing or removing the mastic material along the longitudinal zone extending 45

from the uppermost edge 16 to a line where it forms a shoulder indicated by the numeral 17. The opposite or lower longitudinal boundary of the core is formed with an opposed flange 19 by depressing or removing the mastic from the opposite face of the core, this flange 19 being preferably of a transverse width approximately one-half that of the flange 15 and extending upwardly from the lowermost edge 20 of the core to the point indicated by the shoulder 21. Desirably, the flanges 15 and 19 are each of a thickness one-half that of the main part of the core. They may, however, be of different thicknesses, but in any case, the sum of the thickness of the two flanges should equal substantially the thickness of the main part of the core.

As shown, the reinforcing sheet 11 on the lower face of the core body extends from the upper longitudinal edge 16 thereof to the shoulder 21 adjacent the lower edge. The reinforcing sheet 12, secured to the upper face of the body extends from the shoulder 17 to the lower longitudinal edge 20 of the unit.

The sheet 11, which serves to reinforce the core, preferably consists of a thin sheet of water-resistant material such as asphalt saturated felt of a light grade variety. Materials other than asphalt saturated felt may, however, be used in place of the sheet 11, such for example, as ordinary kraft paper, saturated with asphalt or other waterproof material.

The sheet 12, affixed to the upper face of the element, consists preferably, of a thin grade of asphalt saturated felt, having a layer of asphalt coating on its upper or outermost face, in which said coating is embedded a layer of crushed mineral grit or other wear-resisting and decorative surfacing material 22. The sheet 12 as thus constructed serves not only to increase the structural strength of the finished unit, but also to provide the latter with the desired decorative finish by virtue of the mineral grit 22 which latter can readily be, and is preferably, applied to the sheet 12 in much the same manner as ordinary asphalt coated and mineral surfaced roofing is made, prior to laminating the sheet to the core body 10.

In order that the finished unit shall simulate brick or other masonry construction when laid, the layer of mineral surfacing 22 may be scored transversely or otherwise formed at suitably spaced intervals with transversely extending indicia as indicated at 23 to simulate vertical joints of brickwork. In lieu of scoring the mineral surfacing layer along these narrow transverse zones, the mineral surfacing may be gouged or otherwise removed therealong; or the mineral surfacing may be omitted to expose the black color of the asphalt coating on the sheet 12; or the mineral surfacing at these areas may be covered with suitable paint or the like. In any case, however, it will be preferable that the transverse indicia 23 to simulate vertical mortar joints be provided on the sheet 12 during the fabrication of the sheet, although in some instances it may be desirable to form these indicia in the finished unit after the sheets 11 and 12 have been laminated with the core body 10.

In Figs. 3 and 4, there is shown the arrangement of the units when applied to a vertical side wall. From these figures, it will be seen that the units are laid in successive partially overlapping courses. The adjacent units of each course may be either butted, or slightly spaced from one another along their vertical confronting edges.

Referring particularly to Fig. 4, it will be noted that the units are laid with the wider flanges 15 uppermost and with the opposed lower flange 19 of the units of each course overlapping, to their fullest possible extent, the uppermost flanges 15 of the units of the preceding course, so that the shoulder 21 thereof will be in facial contact with the edge 16 of the units in the preceding course. Likewise, the inner surface of the flange 19 will be in facial contact with the outer face of the flange 15 on the units in the preceding course, along the upper margin thereof. In this way, there is left between the lower edge 20 of each unit in each course and the shoulder 17 of the units in the preceding course, a narrow longitudinal depression of a depth such that the same simulates the horizontal mortar joints of brick or other masonry construction. Also, it will be noted that the arrangement, at the points where the units of each course overlap the units of the preceding course, is such that any water flowing over the surface and entering the horizontal depressions 25 will flow off across the surface of the subjacent units before reaching the supporting structure 26. Thus, in order for water to reach the supporting structure it would be necessary for the water to creep upwardly between the contacting faces of the flanges 15 and 19 and the contacting edges 16 and 21.

The units may be secured to the supporting structure 26 in any suitable and convenient manner, as for example, by nails driven through the flanges 15 before the next succeeding course of units is laid and, if desired, also by means of copper or other rust-resisting nails driven through the exposed portion of the units at suitable intervals therealong.

In Figs. 5 and 6, I have shown means whereby the units as above described, may be produced. In these figures, the numeral 30 represents a nozzle or die which may be attached to any known form of auger or pressure feeding machine for forcing the plastic composition of the core through the die or nozzle 30 by means of which the plastic material of the core is extruded in the form of a continuous sheet or layer issuing from the mouth of the die.

In the arrangement shown in Figs. 5 and 6, the nozzle or die is of a length which will extrude a sheet of the mastic sufficiently wide to make possible the continuous and simultaneous production, longitudinally of the sheet, of five rows of units across the width of the sheet. It will be understood, of course, that this number may be either increased or decreased as conditions may require.

On one side of the nozzle is shown a mandrel indicated at 31 which may be supported in any convenient manner (not shown) and upon which are mounted five slightly spaced rolls or ribbons of sheet material to constitute the reinforcement 11 for the lower face of the body of the units to be formed. The material of each of these rolls will be of a width corresponding to the dimension from the edge 16 to the shoulder 21 of the unit to be formed. Similarly, upon a mandrel 32, located on the opposite side of the nozzle 30, are mounted spaced rolls or ribbons of the asphalt coated and mineral surfaced felt to constitute the outer surface covering 12 for the units. It should be noted that this material is wound in the rolls with the mineral surfaced side thereof on the inside of the successive convolutions.

Below the mouth of the nozzle and slightly forwardly thereof, are arranged a pair of vertically

spaced forming rolls 35, 36, these forming rolls being mounted for rotation upon parallel shafts 37 and 38 respectively, the shafts being suitably journalled in bearings (not shown). The upper forming roll 35 is formed on its surface with a series of collars 39, 39a. In the particular arrangement here shown, the collar 39a is formed at one end of the roll 35 and the four additional collars 39 are formed at spaced intervals axially of the roll corresponding to the transverse dimension from the shoulder 17 to the edge 20 of the units to be produced. Each of the collars 39, 39a is of a width axially of the roll corresponding to the dimension of the flange 15.

The lower forming roll 36 is similarly formed with collars 40, 40a, but in this instance the collar 40a is located at the end of the roll 36 opposite that end of the roll 35 at which collar 39a thereof is located. Also in this instance, the collars 40 are spaced at intervals axially of the roll corresponding to the transverse dimension of the lower face of the unit from the edge 16 to the shoulder 21. The collars 40, 40a are of a width axially of the roll corresponding to the transverse dimension of the flange 19. The collars 39, 39a are of a radial thickness corresponding to the overall thickness of the unit minus the distance from the outer surface of the sheet 11, to the surface of the flange 15, whereas the collars 40, 40a are of a radial thickness corresponding to the overall thickness of the unit minus the distance from the outer surface of the sheet 12 to the surface of the flange 19.

The shafts 37, 38 will be spaced from each other vertically at such a distance that the nip between the surface of the rolls 35, 36, intermediate the collars will be of a thickness corresponding to the overall thickness of the unit to be produced.

By thus arranging the forming rolls 35, 36 and their respective collars, one circumferential edge of each of the collars 39 will rotate substantially in contact with the opposed circumferential edge of the adjacent corresponding collar 40 on the roll 36. This will serve to weaken, if not actually sever, the mastic longitudinally at these points simultaneously with the formation of the flanges 15, 19 by the collars and with the affixing of the ribbons constituting the sheets 11 and 12 to the mastic core body. If desired, these confronting circumferential edges of the collars 39 and 40 may be extended or otherwise formed so as to constitute slitting knives for this purpose. If not so formed, and the units of each row are not severed at this point from the units of the adjacent row, slitting knives may be mounted at any convenient point beyond the apparatus shown in Figs. 5 and 6 for slitting the units of one row from those of an adjacent row.

From the foregoing description, it will be apparent that the ribbons which are to form the sheet 11 of the finished unit may be threaded from the mandrel 31 into the nip between the forming rolls 35, 36 and guided over the portions of the roll 36 intermediate the collars 40 and 40a. Likewise the ribbons of mineral surfaced material to be affixed to the upper surface of the core may be fed from the mandrel 32 and around the surface of the forming roll 35 and into the portions of the nip intermediate the collars 39, 39a. In thus traversing the periphery of the roll 35, each of the ribbons from the rolls on the mandrel 32 will, in passing between and beyond the nip of the forming rolls, become reversed from the position occupied in the rolls so that the mineral surfaced face of these ribbons is outermost with re-

lation to the mastic core body, while the opposite surface of these ribbons becomes affixed to the upper surface of the mastic core.

As the sheet of mastic issues from the mouth of the die 38, it will thus be received between the opposed faces of the ribbons fed from the mandrels 31 and 32 and be carried therewith through the nip between the forming rolls. In passing through the nip, the mastic, as will be more clearly apparent from Fig. 6, will be displaced or deformed on one face thereof by the collars 39, 39a to provide the flange 15 for the units of each row being formed. At the same time, the mastic will be displaced or deformed from the opposite face thereof by the collars 40, 40a and thereby bring to shape the flanges 19 on the units of each row. The adhesive properties of the mastic material of the core, at the elevated temperatures employed as will be understood by those skilled in the art, is sufficient to cause the ribbons or webs on the opposite surfaces thereof to become securely affixed thereto, particularly under the pressure of the rolls 35, 36. If necessary, additional press rolls (not shown) may be located at any convenient point beyond the forming rolls to insure the firm adhesion of the upper and lower ribbons to the core body.

After the ribbons have thus been united and consolidated with the core body, the consolidated sheet may be cooled in any convenient fashion and the finished units of each row severed transversely to any desired length by means of any suitable cutting equipment (not shown), which latter may also include means for slitting the units of the adjacent rows from each other, if this has not already been accomplished, as by the collars on the forming rolls as above described.

The upper ribbons may be fed from the rolls on the mandrel 32 in such manner that the transverse indicia 23 on the several ribbons will be in alignment transversely of the sheet, rather than in the offset relationship shown in Fig. 5 when the ribbons are united with the core sheet. In such case, the transverse severing of the units to desired length may be effected by a single transverse chopper or cutting knife cutting through the units of all of the rows medially of selected ones of the indicia 23, depending upon the length of unit desired and the spacing of the indicia.

In some instances it may be desirable that the units be of tapering cross-sectional thickness transversely thereof. The method and apparatus above described lends itself readily to the production of units as herein described, but of transverse tapering thickness. For this purpose, the surfaces of either or both of the forming rolls, intermediate the collars thereof, as well as the surfaces of either or both sets of collars, may be made of varying diameter. In this way the nip between the forming rolls and the collars thereon may be made to assume the desired taper axially thereof for each row of units to be formed therebetween.

Units such as herein described may be fabricated of greater relative width and provided with flanges corresponding to the flanges 15 and 19 (but which flanges are of equal transverse dimension) and a facing sheet with or without mineral surfacing as desired. Such units would serve well as slabs for flat roof decks, flooring or the like.

Having thus described the invention, and several modes in which the same may be carried out, it will be apparent to those skilled in the art that

various changes may be made therein without departing from the scope thereof as defined in the claims hereto appended.

What I claim as my invention is:

- 5 1. A weather facing building unit comprising a core of hardened plastic material including asphalt, fiber and hardening fillers, said core having an upwardly facing flange on one face thereof along one of its longitudinal edges and a downwardly facing flange on the opposite face thereof along its opposite longitudinal edge, the first named flange being of greater transverse dimension than said second named flange, a layer of asphalt saturated mineral surfaced felt affixed to the first named face, one longitudinal edge of said layer terminating along the inner edge of said first named flange and the other longitudinal edge of said layer terminating along the outer edge of said second named flange, and a smooth surfaced flexible felted material affixed to said opposite face.
- 10 2. A building unit comprising a core of hardened plastic material including asphalt, fiber and hardening fillers, said core having an upwardly facing flange on one face thereof along one of its longitudinal edges and a downwardly facing flange on the opposite face thereof along its op-

posite longitudinal edge, the first named flange being of greater transverse dimension than said second named flange, a layer of asphalt saturated mineral surfaced felt affixed to the first named face, one longitudinal edge of said layer terminating along the inner edge of said first named flange and the other longitudinal edge of said layer terminating along the outer edge of said second named flange, and a smooth surfaced flexible felted material affixed to said opposite face.

3. A surface covering for walls or the like comprising courses of units each of said units comprising a core of hardened plastic material including asphalt, fiber and hardening fillers, each of said cores having an upwardly facing flange along the upper edge of the outer face thereof, a narrower downwardly facing flange along the lower edge of the inner face thereof, a sheet of asphalt saturated mineral surfaced felt secured to said outer face and extending from edge to edge thereof, and a sheet of smooth surfaced felted material secured to said inner face, said narrower flanges of the units in each course partially overlapping the said wider flanges of units in the preceding course.

LESTER KIRSCHBRAUN.
